(57) **CLAIM**

The ornamental design for a multi-well plate assembly, as shown and described.

DESCRIPTION

FIG. 1 is a perspective view of a multi-well plate, according to a first embodiment;

FIG. 2 is a front view of the multi-well plate assembly of FIG. 1;

FIG. 3 is a back view of the multi-well plate assembly of FIG. 1;

FIG. 4 is a right side view of the multi-well plate assembly of FIG. 1;

FIG. 5 is a left side view of the multi-well plate assembly of FIG. 1;

FIG. 6 is a top view of the multi_wellplate assembly of FIG. 1, with an encircled area showing the location of the detail in FIG. 7;

FIG. 7 is an enlarged detail of area 7 within FIG. 6;

FIG. 8 is a bottom view of the multi-well plate assembly of FIG. 1;

FIG. 9 is a perspective view of the multi-well plate assembly of FIG. 1, showing one section of 32-wells being separated;

FIG. 10 is a perspective view of a multi-well plate assembly, according to a second embodiment;

FIG. 11 is a front view of the multi-well plate assembly of FIG. 10;

FIG. 12 is a back view of the multi-well plate assembly of FIG. 10;

FIG. 13 is a right side view of the multi-well plate assembly of FIG. 10;

FIG. 14 is a left side view of the multi-well plate assembly of FIG. 10;

FIG. 15 is a top view of the multi-wellplate assembly of FIG. 10, with an encircled area showing the location of the detail in FIG. 16;

FIG. 16 is an enlarged detail of area 16 within FIG. 15;

FIG. 17 is a bottom view of the multi-well plate assembly of FIG. 10;

(Continued)

FIG. 18 is a perspective view of the multi-well plate assembly of FIG. 10 showing one section of 32-wells being separated;

FIG. 19 is a perspective view of a separated section of 32-wells of the multi-well plate assembly of FIG. 1;

FIG. 20 is a front view of the multi-well plate assembly of FIG. 19;

FIG. 21 is a back view of the multi-well plate assembly of FIG. 19;

FIG. 22 is a right side view of the multi-well plate assembly of FIG. 19;

FIG. 23 is a left side view of the multi-well plate assembly of FIG. 19;

FIG. 24 is a top view of the multi-well plate assembly of FIG. 19; and,

FIG. 25 is a bottom view of the multi-well plate assembly of FIG. 19.

The broken lines in the drawings depict portions of the multi-well plate assembly that form no part of the claimed design.
